R. G. Mason Inventor

By his Attorney S
Bartlett Browne & Co.

UNITED STATES PATENT OFFICE.

ROBERT G. MASON, OF BROOKLYN, NEW YORK.

AUTOMOBILE-RADIATOR.

1,205,771.

Specification of Letters Patent.

Patented Nov. 21, 1916.

Application filed March 16, 1916. Serial No. 84,568.

To all whom it may concern:

Be it known that I, ROBERT G. MASON, a citizen of the United States, residing at Brooklyn, county of Kings, State of New York, have invented a certain new and useful Improvement in Automobile-Radiators, of which the following is a full, clear, and exact description.

My invention relates to improvements in radiators for automobiles and the like, and has for its object to provide an improved radiator, which may be connected up in the ordinary manner, said radiator being so constructed as to have the ordinary cooling ducts and surfaces and in addition a passage which may be used as a by-pass in order to return some of the heated water directly to the engine without passing through cooling passages.

Heretofore, automobiles have been provided with radiators and with by-passes entirely external to the radiator and some automatic means for controlling the passage of water through the by-pass. This is an expensive construction, difficult to install, uncertain in operation, and inconvenient for various reasons.

By my invention I provide a compact construction in which the by-pass is very direct and does not take up any space outside of the space now normally occupied by a radiator. The object of providing the by-pass is to enable the operator of the car to control the temperature of the water in the cooling chambers of the engine so that it may be kept at the temperature best adapted for the operation of the engine, it being well known that in the winter time the water is sometimes cooled to too great a degree while in the summer time as much cooling as possible is ordinarily desired.

The following is a description of an embodiment of my invention, reference being had to the accompanying drawings, in which,

Figure 1 is a rear view of a radiator embodying my invention; Fig. 2 is a vertical section of the same on the line $x-x$, Fig. 1; Fig. 3 is a horizontal section of the same on the line $y-y$, Fig. 2. Fig. 4 is a perspective showing certain details.

Referring more particularly to the drawings, 1 is a radiator frame inclosing the ordinary ducts 2 and cooling surfaces 3.

4 is a baffle plate located above the cooling ducts, having perforations 5, which serve to

distribute the water more or less evenly over the whole top of the radiator ducts.

6 is a port which opens above the baffle plate 4.

7 is a chamber located below the cooling ducts which receives the water therefrom, which water then passes to the water chambers in the engine through the pipe 8.

9 is a by-pass contained within the radiator proper, being nested among the ducts 2 and consisting of a large vertical pipe connecting the chamber 7 with a port 10. The ports 6 and 10 are both connected to a pipe 11, which leads from the upper end of the water chambers of the engine (not shown). Connected to an extension of the baffle plate 4 is a valve 12, the pivot of which carries a gear wheel 13, with which meshes another gear wheel 14, mounted upon a shaft 15, which leads to a knob and indicator 16 located on the dash of the automobile within easy access of the operator. By means of the valve 12 some or all of the water can be diverted around the cooling ducts in the radiator.

In operation the chauffeur turns the member 16 until the indicator is in any desired position, so that the valve 12 directs a corresponding proportion of water through the by-pass and cooling ducts, thus procuring the desired temperature in a simple and efficient manner.

As will be evident to those skilled in the art my invention permits of various modifications without departing from the spirit thereof, or the scope of the appended claims.

What I claim is:

1. In a radiator, the combination of a radiator frame, cooling ducts contained within said frame, a by-pass also contained within said frame, said cooling ducts and by-pass discharging into a common return, a valve controlling the flow of water to said cooling ducts and to said by-pass, and means for controlling said valve.

2. In a radiator, the combination of a radiator frame, cooling ducts contained within said frame, a vertical by-pass, said cooling ducts and by-pass discharging into a common return, a connection having an upper port and a lower port, a valve coacting with said ports for controlling the flow of water to said cooling ducts and to said by-pass, means for controlling said valve, and a baffle plate above said cooling ducts and by-pass and between said ports, so that

water is discharged from said first mentioned port above said baffle plate, the amount depending upon the position of said valve.

3. In a radiator, the combination of a radiator frame, cooling ducts contained within said frame, a vertical by-pass also contained within said frame, said cooling ducts and by-pass discharging into a com-

mon return, a valve controlling the flow of 16 water to said cooling ducts and to said by-pass and means for controlling said valve, said valve having an axis of rotation which is horizontal, said by-pass being located midway between the sides of said frame, said 15 valve being located adjacent to the upper ends of said cooling ducts and by-pass.

ROBERT G. MASON.
